RELAY.

1,384,948.

Specification of Letters Patent. Patented July 19, 1921.

Application filed September 29, 1919. Serial No. 327,067.

To all whom it may concern:

Be it known that I, GEORGE R. GUILD, a citizen of the United States, and an officer of the United States Army, stationed at Baltimore, Maryland, have invented a certain new and useful Improvement in Relays, of which the following is a full, clear, and exact description, such as will enable others skilled in the art to which it appertains to make and use the same, reference being had to the accompanying drawings, forming part of this specification.

My invention relates generally to new and useful improvements in relays and more particularly to a relay designed for use in connection with the electrical circuits of practically all forms of signaling systems and particularly those systems utilized in connecting with railways for the guidance and control of trains.

The principal objects of my invention are, to generally improve upon and simplify the existing types of relays; to provide a relay having but two coils or solenoids; to combine with said relay relatively simple connections between the rails of a section or block of a railway track; to arrange in said connections visible signals to be observed by the engineer or train operator; and to provide a relay and signaling system that possesses superior advantages in point of simplicity, economy and general efficiency.

With the foregoing and other objects in view, my invention consists in certain novel features of construction and arrangement of parts, hereinafter more fully described and claimed, and illustrated in the accompanying drawings, in which—

Figure 1 is a diagrammatic view of a relay of my improved construction, the operating parts thereof being in neutral position and said relay being associated with the rails of a railway track and with signal lamps adjacent to said track.

Fig. 2 is a vertical section taken through the center of the housing for the relay and showing the relative positions of the parts therein.

Figs. 3 and 4 are diagrammatic views of the relay, the armature and contact carrying member of which relay are in shifted

positions and said views showing the active circuits in heavy lines.

Fig. 5 is a diagrammatic view of my improved relay and showing its connections with a block or track having turn-outs or side tracks.

Fig. 6 is a diagrammatic view illustrating the arrangement of my improved relay in connection with a standard relay for open or closed circuit signal circuits.

Fig. 7 is a diagrammatic view of my improved relay and showing its connection with a two-position combined turn-out and block signal.

Referring by numerals to the accompanying drawings, and particularly to the construction illustrated in Figs. 1 to 4 inclusive, 10 designates a box-shaped housing provided with a removable top 11 and with a horizontally disposed partition 13. Formed in this partition 13 is an aperture 14 and passing therethrough is a shaft 15, the ends of which are journaled in suitable bearings 70 on the top 11 and on the bottom of housing 10.

Secured to the lower portion of shaft 15 in any suitable manner and projecting horizontally therefrom is an armature 16, the free end of which is disposed between the cores of a pair of solenoid coils 17 and 18. A relatively light spiral spring 15^a has its inner ends secured to shaft 15 and its outer end secured to the underside of partition 13, which spring normally maintains said shaft and the armature 16 carried thereby in neutral position between the cores of the solenoids as illustrated in Fig. 1.

Positioned on shaft 15 above the partition 13 is a disk 19 of insulating material such as hard rubber or fiber and arranged in or near the periphery thereof and immediately adjacent to each other are metal contact members 20 and 21. Arranged upon or adjacent to the periphery of the disk 19 and disposed substantially at right angles to these contact members 20 and 21 is a pair of contact members 22 and 23. Arranged upon or adjacent to the periphery of disk 19 and preferably diametrically opposite from the contact members 20 and 21 are three contact members 24, 25 and 26.

Fixed on partition 13 and projecting up-

wardly therefrom is a yielding contact member 27, preferably resilient metal, the free end of which is adapted to engage in any one of the contact members 24, 25 and 26. 5 Leading from this contact member 27 to one side of the battery 28 is a conductor 29 and leading from the other side of said battery to a red signal lamp 30, a green signal lamp 31 and a yellow signal lamp 32 is a conductor 33. A conductor 34 connects red lamp 30 with contact member 26; a conductor 35 connects green lamp with contact member 25; and a conductor 36 connects the yellow lamp 32 with contact member 24. 10 A conductor 37 connects contact member 23 with one end of the coil of solenoid 17 and the other end of said coil is connected to contact member 20 by a conductor 38. A conductor 39 connects contact member 22 with one end of the coil of solenoid 18 and the other end of this coil is connected to contact member 21 by a conductor 40.

Arranged on partition 13 is a flexible contact member 41, preferably a resilient strip of metal, the free end of which is adapted to engage either one or both of the contact members 22 and 23. Leading from this contact member 41 to a battery 42 is a conductor 25 43 and leading from said battery to the continuous or unbroken track rail 44 of a block or section of railway track is a conductor 45. The opposite rail of the track is open or broken, thereby forming sections 46 and 47, 30 and connecting the rail sections 46 with a resilient contact member 48 that is fixed on partition 13 and adapted to engage contact member 20 is a conductor 49.

Arranged on partition 13 is a resilient contact member 50 which is adapted to engage contact member 21 and leading from said contact member 50 to conductor 49 is a conductor 51. Located adjacent to resilient contact member 50 is a resilient contact member 52 that is adapted to engage contact member 21, and leading from said contact member 52 to rail section 47 is a conductor 53. Located adjacent to contact member 48 is a resilient contact member 54 45 that is adapted to engage contact member 20 and leading from said contact member 54 to conductor 53 is a conductor 55.

Under normal conditions, solenoid 17 is in series with that portion of the block in 50 which rail section 46 is located and solenoid 18 is in series with that portion of the block of which rail section 47 forms a part. Thus both solenoids or coils are at all times ready to be energized from battery 42 by the trucks 60 of a locomotive or car on either portion of the block. For instance, a locomotive or car entering the block in which rail section 46 is located will cause track battery 42 to discharge current through the circuit including 65 conductor 43, contact member 41, contact

member 23, conductor 37, solenoid 17, conductor 38, contact member 20, contact member 48, conductor 49, rail section 46 through the wheels and axles of the truck, as designated by X, Fig. 3, thence through continuous rail 44 and from thence through conductor 45 back to battery. 70

As this circuit is thus energized, solenoid 17 will attract armature 16, thereby rotating shaft 15 and the disk 19 clockwise a short distance, and the parts will then assume the positions illustrated in Fig. 3 with contact member 24 in engagement with contact member 27, thereby closing the circuit in which yellow lamp 32 is located, and as a 80 result said yellow lamp will burn to give visible warning that there is a locomotive or car upon that portion of the block in which rail section 46 is located.

It will be understood that prior to the 85 partial rotation of disk 19 as just described, or while the parts are in normal position, as illustrated in Fig. 1, contact members 25, and 27 are engaged, thereby closing the circuit in which green lamp is located and 90 said green lamp burns to make a visible signal and indicate that the block with which this particular lamp and relay are associated is clear or open.

As the disk 19 is thus rotated clockwise 95 contact member 20 will engage both contact members 48 and 54, and contact member 21 will move out of engagement with contact member 52, thus putting both rail sections 46 and 47 individually in circuit with solenoid 17 only and cutting solenoid 18 entirely out of circuit.

As a result of the operations just described, the green lamp is cut out of circuit and the yellow lamp cut into circuit, and the latter will continue to burn during the passage of the locomotive or car through the block notwithstanding the fact that said locomotive or car crosses the break or opening between rail sections 46 and 47. 105

In the event that a locomotive or car enters the end of that portion of the block in which rail section 47 is located, (see Fig. 1) the circuit in which solenoid 18 is located will be closed with the result that the free end of armature 16 will be attracted by the core of 110 said solenoid, thereby partially rotating the disk 19 anti-clockwise and such action brings about an engagement of the contact members 26 and 27, thereby closing the circuit in which red lamp 30 is located, and as a result said red lamp will burn to give 115 warning of the presence of a locomotive or train in the block with which the relay is associated, and such condition will be maintained during the entire passage of the locomotive or train through the block.

Further, the relay may be used with open or closed circuit signal circuiting, as shown in Fig. 6, and if desired, the relay may be 120

operated by means of secondary track relays of either direct or alternating current design, and where this is done it is not necessary to connect the relay directly to the rail circuit.

In Fig. 5 I have shown the application of my improved relay to a turn-out or side track in a block. In this construction, disk 19^a is carried by armature 16^a, the free end 10 of the latter being disposed between the inner ends of coils 17^a and 18^a. Carried by disk 19^a is a pair of contact members 60 and 61 and said disk also carrying a second pair of contact members 62 and 63.

15 Adapted to engage with either contact member 60 or 61 is a stationary contact member 64 and leading therefrom to a battery 65 is a conductor 66. Leading from the other side of this battery to a red lamp 67 and a green lamp 68 is a conductor 69, and leading from red lamp 67 to contact member 61 is a conductor 70. Leading from green lamp 68 to contact member 60 is a conductor 71. Leading from contact members 62 to coil 17^a is a conductor 72, and leading from said coil to rail section W is a conductor 73. A stationary contact member 74 is adapted to engage either or both of the contacts 62 and 63 and leading from 20 said contact member 74 to a track battery 75 is a conductor 76. Leading from the track battery 75 to a rail section S is a conductor 77. Leading from contact member 63 to coil 18^a is a conductor 78, and leading 25 from said last mentioned coil to a rail section P is a conductor 79. Located at the opposite end of the block and adjacent to the turn-out rail sections M and J are red and green lamps 80 and 81 respectively, and 30 leading thereto from the battery 82 is a conductor 83. Leading from these lamps to contact members 84 and 85 are conductors 86 and 87, respectively, and adapted to engage the contact members 84 and 85 is the 35 end of a spring-held armature 88 that is connected to battery 82.

A relay 89 is arranged in position to attract armature 88, said relay being connected to rail section M by a conductor 90 and to rail section P by a conductor 91. Where it is desired to provide a turn-out signal without interfering with the block signaling system, a conductor as shown by 40 92, Fig. 7, connects solenoid 18^a with relay 89 and when this construction is carried out, it will be understood that the conductors 79 and 91 are eliminated. In other words, for the block signaling system, the conductors 79 and 91 are provided, but for 45 the turn-out signaling system, these conductors are eliminated, and a conductor such as 92 is installed.

50 Referring to Fig. 7 and assuming that the relay is being utilized in a turn-out signaling system and that a locomotive or car

has entered that portion of the block in which rail section W is located and that at the same time or immediately thereafter, a locomotive or car enters the portion of the block in which rail sections M and J are 55 located, the car on the section of the block which includes the rail W and which car enters the block first will cause battery to discharge current through conductor 76, contacts 74 and 62, conductor 72, coil 17^a, 70 conductor 73, rail section W, wheels and axles of the truck on the rails W and H, and from the rail section H through a part of rail S and from thence through conductor 77 to battery. 75

Thus coil 17^a will be energized which attracts armature 16^a, consequently moving disk 19^a clockwise. When the disk has been thus moved, the contacts 74 and 62 are still 80 in engagement, but contacts 63 and 74 are 85 out of engagement. Consequently as long as the car is on the section of track in which rails H and W are located, coil 18^a cannot get current, and consequently there can be 90 no current flow through conductor 92 and the car or locomotive on the section of the track including rails M and J cannot affect or move the disk of the relay.

When the disk of the relay is in neutral 95 position, contacts 61 and 64 are in engagement and consequently red lamp 67 is receiving current from battery 65 and is burning but upon the clockwise movement of disk 19^a, contacts 61 and 64 are disengaged and contacts 60 and 64 engaged, thereby cutting out the circuit in which red lamp is located and cutting in the circuit in which the green lamp is located. Consequently it is possible for the locomotive or car on the portion of the block including rails H and 100 W to effect a turning movement of the disk 19^a clockwise, and the red lamp will be extinguished and the green lamp will be lighted and at the same time the conditions will be such that the locomotive or train 105 on the opposite end of the block or that portion including the rails M and J cannot get current from battery 75 through coil 18^a and conductor 92. Hence the car or locomotive upon rail sections H and W and 110 which was the first to enter the block cuts out its red signal lamp 67 and causes its green signal lamp 68 to burn and therefore the engineer of said locomotive or train 115 may enter and pass through the block with safety. Had the car or locomotive at the end of the block including rail sections M and J entered the block first, then the disk of the relay would be turned counter clockwise by the action of coil 18^a on armature 120 16^a and in such event battery 75 discharges current through conductor 76, contacts 74 and 63 (contacts 74 and 62 being disengaged), conductor 78, coil 18^a, conductor 92, 125 relay coil 89, conductor 90, rail section M 130

through the wheels and axles of the truck to rail section J, from thence through rail S and conductor 77 back to battery. This counter clockwise movement of the disk 5 maintains the circuit in which the red lamp at the lefthand end of the block is located and thus prevents a car or locomotive entering this lefthand end of the block from actuating the relay and cutting out its red 10 signal and cutting in the green signal.

Referring to Fig. 5 and assuming a car to have entered the lefthand end of the block or that portion including the rails H and W, such car, the block being clear, cuts 15 out the circuit in which the red lamp is located and cuts in the circuit in which the green lamp is located and with such circuit the car may enter and pass through the block during which time or while the green 20 lamp is burning the green lamp 81 at the opposite end of the block cannot (due to the position of the disk as previously described) receive current and burn. As the forward trucks of the car pass onto the rail 25 section P, the rear trucks will maintain the green signal and such signal will be maintained as long as any portion of the car or train is upon the rail sections H and W.

Assuming a car to have entered the block 30 with no portion of the car on rail section W, then the disk will immediately return to normal position and then move counter-clockwise by the energized coil 18^a which attracts armature 16^a. As a result current 35 from battery 75 passes through conductor 76, contacts 74 and 63, conductor 78, coil 18^a, conductor 79, rail section P, through the wheels and axles of the truck to rail section S, from thence through conductor 17 40 to battery 75.

Thus the presence of a car on that portion of the block including rails P and S energizes coil 18^a and although relay coil 89 is in multiple with the car on the rails P 45 and S, in case there is a car on that portion of the track including rails M and J, coil 89 cannot be energized due to the fact that the car on the rails P and S shunts said coil out 50 of circuit. Therefore, a car entering the lefthand end of the block causes the red signal lamps at both ends of the block to burn and preventing a car entering either end of the block from cutting out the red signal lamps and cutting in the green lamps.

Assuming that a car enters the end of the block in which rails M and J are located 55 and that the block is clear, then current will be discharged from battery 75 through conductor 76, contacts 74, 63, conductor 78, coil 18^a (hence turning the disk counter clockwise, thereby cutting the green lamp at the lefthand end of the block out of circuit), conductor 79, rail P, conductor 91, relay coil 89 (which attracts armature 88 and closes 60 the circuit to green lamp 81), conductor 90,

rail M, cross the wheels and axles of the truck to rail J through rail S and conductor 77 to battery. Therefore, this car cuts out the red signal lamp 80 and comes into circuit with the green lamp 81, and prevents 70 the green signal lamp at the opposite end of the block from burning. As the car passes from rail M onto rail P, the forward trucks establish circuit between rails P and S while the rear trucks maintain the 75 circuit between rails M and J with the result that coil 18^a does not release armature 16^a, and consequently the red signal lamp 67 at the lefthand end of the block burns even though a car may have entered this end 80 of the block.

Therefore, it will be seen that my improved relay can be advantageously used in connection with a turn-out signaling system (Fig. 7) without interfering with the 85 block signaling system and where so used, the conductor 92 (Fig. 7) is utilized and the conductors 79 and 91 to the track rail P eliminated or disconnected. Where the relay is used in connection with a combined 90 turn-out and block signaling system, the conductor 92 is eliminated or cut out of circuit, Fig. 5.

It will be understood that the relay is not necessarily connected directly to the 95 track rails as illustrated and herein-described, but that secondary relays may be employed and impedance bonds and alternating current used instead of direct current and insulated breaks.

A relay of my improved construction is relatively simple, can be easily and cheaply manufactured, and is very effective in performing its intended functions.

It will be readily understood that minor 105 changes in the size, form and construction of the various parts of my improved relay may be made and substituted for those herein shown and described, without departing from the spirit of my invention, the 110 scope of which is set forth in the appended claims.

I claim:

1. The combination with a railway track having a continuous rail and a broken or 115 open rail, of a relay including a pair of solenoids, each of which is connected in series with one of the sections of the broken or open rail and with the continuous rail, an armature pivotally mounted between said 120 solenoids and adapted to be attracted thereby when they are energized, and rotatable means adjacent to the armature for cutting one of said solenoids out of circuit when the other solenoid has been energized to attract 125 the armature.

2. The combination with a railway track having a continuous rail and a broken or 130 open rail, of a relay including a pair of solenoids, each of which is connected in series

- with one of the sections of the broken or open rail and with the continuous rail, an armature pivotally mounted between said solenoids and adapted to be attracted there-
5 by when they are energized, means for cutting one of said solenoids out of circuit when the other solenoid has been energized to attract the armature, a plurality of signal lamp circuits, a member positioned above
10 the armature and movable therewith, and means on said member for closing one of said lamp circuits depending on the position of said member.
3. The combination with a section of rail-
15 way track having a continuous rail and an open or broken rail, of a solenoid in circuit with said continuous rail and one of the sections of the broken rail, a second solenoid in circuit with the continuous rail and the
20 other section of the broken rail, an armature pivotally mounted between said solenoids and adapted to be actuated upon the closing of either one of the circuits in which the solenoids are located, a plurality of signal lamp circuits, and means adjacent to the armature and controlled thereby for closing
25 one of said lamp circuits upon the closing of the circuits in which the solenoids are located.
- 30 4. The combination with a section of rail-
way track having a continuous rail and an open or broken rail, of a solenoid in circuit with said continuous rail and one of the sections of the broken rail, a second solenoid in circuit with the continuous rail and the
35 other section of the broken rail, an armature pivotally mounted between said solenoids and adapted to be actuated upon the closing of either one of the circuits in which the solenoids are located, a disk provided with
40 contacts adjacent to and movable with said armature, and a plurality of lamp circuits provided with a contact which is adapted to be engaged by the contacts on the member carried by the armature.
5. The combination with a section of rail-
way track having a continuous rail and an open or broken rail, of a pair of solenoids, each of which is in circuit with the continuous rail and one of the sections of the open or broken rail, a relatively stationary contact member in said circuits, a pivotally mounted armature adapted to be attracted by said solenoids, a disk adjacent to said armature, contact members carried by said member and adapted to engage the relatively stationary contact member to close the circuits in which it is located, a plurality of signal lamp circuits, and means for closing
50 one of said lamp circuits when either circuit between the continuous rail and the sections of the broken rail is closed.

In testimony whereof I hereunto affix my signature this 19th day of September, 1919.

GEORGE R. GUILD.
